UNITED STATES PATENT OFFICE.

JULIUS BRENZINGER, OF FAIRFIELD, CONNECTICUT, ASSIGNOR TO THE MAX AMS MACHINE COMPANY, OF NEW YORK, N. Y., A CORPORATION OF NEW YORK.

SIDE-SEAM-SOLDERING MACHINE FOR CAN BODIES.

1,419,211.

Specification of Letters Patent. Patented June 13, 1922.

Application filed October 6, 1919. Serial No. 328,678.

To all whom it may concern:

Be it known that I, JULIUS BRENZINGER, a citizen of the United States, and a resident of Fairfield, in the county of Fairfield and 5 State of Connecticut, have invented certain new and useful Improvements in Side-Seam-Soldering Machines for Can Bodies, of which the following is a specification.

This invention relates generally to mechanism appurtenant to can-body forming machines for applying solder exteriorly to the interlocked side seams of the formed can bodies.

The modern so-called "sanitary" can is 15 the result of efforts to eliminate solder, partly for the purpose of effecting a substantial increase in the output capacity of forming and heading machines beyond the maximum possible with approved all-soldering processes, and partly on account of the real or supposed objectionable results of the chemical action of the acids of fruits and other packed perishable food products upon solder and the residue of the necessary 20 fluxing operations preliminary to soldering. The well-known double-seaming process of securing the end or top and bottom portions to the body portions of so-called tin cans effects a permanent air-tight seam rapidly, 25 expeditiously and without the use of solder, the intercurling and compressing of curved edges of the sheet metal resulting in the formation of a joint of even greater strength than was possible under any of the old soldering processes.

Can bodies, particularly those of the cylindrical or "round" type, are formed from flat sheet-metal blanks which are curled or curved around a suitable mandrel, opposite 30 end edges of each blank having been bent or folded back to provide oppositely-disposed hooks whereby these end edges may be interhooked during and at the end of the forming operation and the interhooked portions then compressed to produce a substantially solid seam. Theoretically, of course, if the pressure has been sufficient, this seam may be made strong and hermetic, but in practice, particularly under present necessary 35 conditions of great rapidity of operation of machines, a seam so formed is not considered to be in itself sufficiently dependable. It is, however, of such character that solder may be applied to the exterior there-

of in a manner to insure impermeability and 55 the requisite strength practically without the slightest risk of any of the solder reaching the interior of can body and without the necessity of curtailing the maximum output capacity of forming and heading machines 60 of approved modern construction and operation. Therefore, it has been found desirable, and it is the present practice, to apply solder exteriorly to the hook-formed or so-called interlocked side seams of can bodies. 65

To apply the solder to these side seams, it has been the general practice to pass the formed can body from the mandrel to a horn or track which supports the body interiorly and along which it is conveyed with 70 the side seam for a time in contact with a rotating roller which dips into a bath of molten solder. In connection with such a soldering process, at least two essentials are 75 instantly apparent. First, the horn being relatively of considerable length, while one end thereof may be rigidly supported by the mandrel, of which it may be said to be a continuation, the other end thereof must be so supported as to permit of the ready 80 passage of the surrounding can bodies along the same during the soldering operation and ultimate discharge of said bodies from the far or free end thereof. Second, the can bodies must be held against rotation 85 while in transit along the horn, for if permitted to rotate thereon under the frictional forces generated by the rotating soldering roller in contact therewith, the seam to be soldered would be carried out of contact with the roller and the solder applied 90 uselessly to the flat side of the blank.

In-so-far as the above-recited first essential is concerned, the free end of the horn undoubtedly may be—and in many types 95 of side-seam soldering machines now in use is—supported upon a roller or rollers between which and the horn the advancing can body may be passed; but it has been found that owing to the weight of the roller-supported parts and the consequent resistance to movement of the can body along the horn at the point or points of support, said body—and, particularly, the freshly soldered side seam thereof—is likely to be 100 and frequently is unduly distorted. Therefore, it is undoubtedly most desirable that the horn be so supported as to permit of

absolutely free, unobstructed and unimpeded passage of the can body along and ultimately off the horn.

In-so-far as the above-recited second essential is concerned, in a co-pending application, filed by me January 31, 1919, Serial No. 274,194, I have shown and described means for conveying can bodies successively from the forming mandrel to and along the horn under action of the rotating soldering roller with each of said bodies held against rotation on said horn. As at present advised, I prefer to incorporate these means in the machine of the present invention, although it is to be understood that this invention is not to be limited to any specific form or type of means for preventing rotation of the can bodies while in transit on the horn, the principal object of the invention being the provision of a machine in which the free end of the horn is supported in the manner and for the purposes generally outlined in the foregoing paragraph.

As stated in my co-pending application, aforesaid, a soldering machine of the type herein shown and described is primarily designed to form a link in a chain of machines which cooperate progressively to produce a completed can body, with its end flanges, from a flat sheet-metal blank. In spite of a high degree of perfection of machinery and the utmost care in the operation thereof, due to irregularities and imperfections in the metal operated upon, and other unavoidable causes, blanks become distorted and jammed in the forming mechanism and deliveries of formed can bodies to the soldering horn are checked. Obviously, operation of the forming mechanism at least must be instantly stopped, for clearance and readjustment, but, in the mean-time, soldered and partially soldered can bodies are on the horn, the former still to undergo the finishing or "wiping" operation and the latter with the soldering operation uncompleted. Undoubtedly, the soldering, wiping and discharging operations should be continued in connection with can bodies which have already been delivered from the mandrel to the horn, and obviously operation of the entire chain of machines, or even of the forming mechanism alone, cannot practicably be continued for this purpose. Therefore, the mechanism for rotating the soldering roller, that for rotating the finishing or wiping brush, and that for advancing the can bodies along the horn and effecting ultimate discharge thereof should be capable of immediate disconnection at any time from all other mechanisms and any common source of power, so that independent operation of the former, either by hand or power, may be continued after operation of the latter—and, particularly, the forming mechanism—has been stopped.

Another object of the invention, therefore, is the provision of means—such, for example, as the interposition of a clutch and means for independent hand actuation—for continuing operation of the can-body advancing, soldering and finishing mechanisms independently after checking operation of mechanism or mechanisms comprising another or other parts of the chain of machines.

Other minor although possibly important objects of my invention are believed to be made apparent in the following specification, in which I have described a practical and convenient embodiment of the invention, reference being had to the accompanying drawings, forming a part hereof, in which—

Fig. 1 is a side elevation of that portion—approximately one-half—of a machine embodying my invention adjacent to the blank-forming machine;

Fig. 2 is a similar view of the remainder of the machine, the same being a continuation of Fig. 1;

Figs. 3 and 4 are plan views of Figs. 1 and 2, respectively;

Fig. 5 is a slightly enlarged vertical cross-section, taken substantially on the line 5—5 of Fig. 3;

Fig. 6 is an enlarged plan view of a portion of Fig. 4, showing the can body in the position of being fed from the horizontally-disposed conveyer-chain into the path of the vertically-disposed conveyer-chain, as hereinafter described;

Fig. 7 is an enlarged side elevation of a portion of Fig. 2, partly in section, showing the can body about to be discharged from the horn, and

Fig. 8 is an end elevation of Fig. 6.

As hereinbefore suggested, the machine of the present invention is primarily designed to be appurtenant to what is known as a can-body forming machine, such, for example, as the machine—or the forming mechanism which is a link in the chain of inter-related mechanisms—shown and described in patent to Paul R. Hahnemann, dated October 3, 1916, No. 1,200,190, in which means including a yieldingly contractile mandrel are provided for forming a can body from a flat sheet-metal blank, interlocking the hook-formed ends thereof, compressing the inter-hooked end portions to form a seam, and ejecting the formed can body from the mandrel.

Referring now to the accompanying drawings in detail, numeral 11 designates the body-forming mandrel, or an extension thereof, to which I have shown telescopically connected, for purposes of guiding and support, one end of the horn or track 12, preferably comprising guide-rails 13 and 14, spaced apart by blocks 15 located at in-

5 tervals throughout the length of said rails, adapted to receive the formed can body from the mandrel and guide its further advancement, the whole being laterally dimensioned and shaped to conform to the contour 10 of a can body of standard size and tend to preserve such contour as said body and those following are advanced along the same.

10 The supporting frame of the machine may and preferably does include the side-bars—channel-bars, as shown—16 and 17, supported from the floor by means of the legs 18 18, and carried by this frame near what may be termed the mandrel-end thereof is 15 an elongated tank 19 adapted to contain molten solder. A pipe 20, leading from any suitable source of supply of inflammable gas, terminates in a burner 21, whereby the contents of said tank 19 may be kept in a 20 heated and therefore molten condition. Rotatively mounted to dip into the molten solder 22 in the tank 19 is the roller 23. Obviously, upon rotation of said roller, a 25 film of molten solder will adhere thereto and be carried upwardly on the upwardly-rotating side thereof.

30 Suitably journaled in the frame of the machine and—in the machine shown—in a standard 24 secured to the floor is a horizontal shaft 25, driven in any desired and approved manner from a source of power which, for purposes of synchronization, is common to both forming and soldering mechanisms, as by a chain from a primary 35 driving element passing around a sprocket 26 on said shaft, the sprocket 27 thereon serving through a similar connection to drive the forming mechanism—the latter not being shown in view of the fact that except 40 for the connection therewith it forms no part of the present invention. Mounted on this shaft 25 is the bevel-gear 28 the teeth of which mesh with the teeth of a similar gear 29 on a shaft 30 journaled in brackets 45 or arms 31 and 32 carried by the side-bar 17 of the frame. The soldering roller 23 is rotated from the shaft 30 by means of a belt 33 which passes around pulleys on the axle 34 of said roller and said shaft, respectively. 50 As stated, the tank 19 is located near that end of the horn or track 12 adjacent to the mandrel (or extension) 11, and the roller 23 is so positioned and adjusted relative to said horn or track that as a can body 35 is advanced along said horn from the mandrel the interlocked side seam 36 of said body may be held in contact with the cylindrical face of said roller, as shown in Fig. 5. In a manner too well known to require detailed 60 description here, upon rotation of said roller with its cylindrical face in contact with the seam of the advancing can body, a portion of the film of solder adhering to the roller will be more or less uniformly scraped off 65 by the seam edge and be deposited in the ex-

terior interstice of the seam to fill, seal and strengthen the same.

70 After the soldering operation, interior support of the can body should be continued until the solder has become hardened or "set" by cooling. Furthermore, my improved horn-supporting means requires a certain definite amount of space for successful operation, which space cannot form any part of that occupied by the tank and the 75 soldering mechanism. Therefore, the horn or track 12 is made to extend a considerable distance beyond the end of the tank 19. To advance the can bodies successively from the mandrel along that portion of the horn or 80 track which is contiguous to the soldering mechanism, where the can body actuating and controlling means cannot well be located below the horn, I provide an endless conveyor-chain 37 passing around idler sprockets 38, 39 and 40 and around the driving sprocket 41 mounted on a short vertical shaft 42 which is journaled in bearings in the bracket 43 carried by the side-bar 17 of the 85 frame.

90 Aligned with the shaft 30 and similarly carried by the frame of the machine is a shaft 44, a clutch 45 (the function and operation of which will be hereinafter described) being interposed between these 95 shafts whereby under ordinary or normal conditions they rotate as one, the latter being driven by the former. On the shaft 44 is mounted a bevel-gear 46 the teeth of which mesh with the teeth of a similar gear 47 on the short vertical shaft 42 whereby the 100 sprocket 41 is driven and thereby the conveyor-chain 37.

105 As set forth in my co-pending application, aforesaid, in order that the can bodies may travel freely along the horn or track 12 they must be loose thereon, and, if loose, and pressed with sufficient force against the rotating roller 23 to effect the proper application of solder to the seam 36, the roller will 110 tend through friction to rotate the can body on the horn and thereby displace the seam. It has been found, therefore, that it will not suffice merely to provide the chain 37 with 115 lugs or fingers adapted to engage the ends of the can bodies in a common and well-known manner to advance the latter, but that means must be provided to engage the bodies in such manner as to hold them against rotation on the horn or track. For 120 this purpose, in addition to the ordinary pusher-lugs or fingers 48 with which certain links 49 of the chain 37 are provided, at suitable intervals, each adapted to engage the end of a can body as it is ejected from the 125 mandrel and advance said body along the horn or track and through the soldering mechanism, I mount upon certain other links 50, proper distances in advance of the links 49 (Fig. 6) yieldingly engaging gripping 130

devices 51 the construction and operation of which are shown and described in detail in my co-pending application, aforesaid. Therefore, for the purposes of this description, it will suffice to state that the can bodies 35 are advanced from the mandrel through the soldering mechanism by the lugs or fingers 48 and held against rotation on the horn or track 12 during this portion of their advancement by the devices 51.

At the end of the shaft 44 is mounted a bevel-gear 52 the teeth of which mesh with the teeth of a similar gear 53 on a shaft 54 journaled in suitable bearings in the side-bars 16 and 17 of the frame. At the end of the shaft 54 is mounted a pinion 55 in mesh with a gear 56 on a short shaft 57 journaled in bearings in the frame-bar 17. Journaled in bearings in brackets or arms carried at the ends of the track-trails 62 and 63, mounted on the frame-bars 16 and 17 and which will be hereinafter described, is the shaft 58, mounted on one end of which is a sprocket 59 around which passes a chain 60 which also passes around a sprocket 61 on the driven shaft 57, whereby the shaft 58 is rotated. Journaled in bearings in similar brackets or arms at the other ends of the track-trails 62 and 63 is the shaft 64, and parallel conveyer-chains 65 and 66 pass around sprockets 67 and 68, respectively, on the driven shaft 58 and idler sprockets 69 and 70, respectively, on the shaft 64. End portions of the conveyers 37 and 65—66 overlap in relative longitudinal positions, whereby can bodies delivered after advancement by the former may be picked up by the latter and advancement continued to the point of final delivery.

The chains 65 and 66 include special links 71 arranged in pairs the members of which are oppositely positioned and the pairs being spaced apart a distance which somewhat exceeds the length of the maximum size of can body which the machine is designed to accommodate. Each pair of links 71 carries a cross-bar 72 at the middle of which is provided the pusher-lug or finger 73 adapted to engage the end edge of a can body and advance the same with said chains, as best shown in Fig. 7. Journaled in bearings in each pair of said links 71 is a shaft or axle 74 carrying rollers 75 and 76. Between the side-bars 16 and 17 of the frame are provided cross-bars 77 upon which are mounted the track-trails 62 and 63, hereinbefore referred to. These track-trails are positioned and grooved (as shown in Fig. 8) for the reception and guidance of the rollers 75 and 76, respectively, whereby these rollers and therefore the shaft or axle upon which they are mounted are positively supported as the special chain-links 71 are advanced. On each shaft or axle 74 is also mounted, rotatively, a roller 78, and the free end of the horn or track 12 is supported

upon a longitudinally disposed channel-bar 79 through the interposition of pedestals 80 between said channel-bar and each of the blocks 15 at this end of the horn. The channel-bar 79, in turn, is supported upon the rollers 78, for which it provides a run-way.

It will now be apparent that the free end of the horn or track 12 is at all times properly and adequately supported, while, at the same time, the supports are traveling with the advancing can bodies therebetween, wherefore the latter are never passed between the horn and its support or supports and movement thereof is continuously unobstructed and unimpeded.

The clutch 45, releasably connecting the shafts 30 and 44, is of conventional construction and operation, the connection being normally effective and the shaft 44 being released by shifting the lever 81. Now, if blanks become distorted and jammed in the forming mechanism with can bodies on the horn or track 12 in progressive stages of the soldering operation, the lever 81 may be thrown to release the clutch 45 and thereby, so far as power transmission is concerned, segregate the soldering and can-body-advancing mechanisms, whereupon, the primary source of power having been disconnected through operation of a belt-shifter, clutch or other common and well-known instrumentality, actuation of said mechanisms may be continued independently until completion of the soldering operations on all can bodies theretofore delivered from the mandrel to the horn and clearance of all can bodies therefrom.

As a preferred means of continuing independent operation of the soldering and can-body-advancing mechanisms, I have shown a hand-wheel 82 mounted on the shaft 42, on which is also mounted the driving sprocket 41. Upon releasing the clutch 45, this hand-wheel 82 may be turned, thereby operating said mechanisms independently to complete the soldering operations on can bodies already delivered to the horn and clear the latter.

Numeral 83 refers to an ordinary fluxing roller mounted on a short shaft 84, dipping into a flux box or container 85 and performing its function in the usual manner. I have shown the shaft 84 driven from the shaft 25 by means of a cord-belt 86 passing around grooved pulleys 87 and 88 on said shafts, respectively.

Numeral 89 designates the usual "wiping" roller, designed to remove the surplus solder and otherwise "finish" the soldering operation. I have shown the same mounted on a short shaft 90 and driven from the shaft 54 by means of a chain 91 passing around suitable sprockets on said shafts.

To accelerate natural cooling of the parts,

including the advancing can body, and therefore the hardening or "setting" of the applied solder, I have shown mounted between the track-rails 62 and 63 an elongated 5 cylindrical shell 95, providing an air chamber into which air is directed from one or more supply-pipes 96 leading from any suitable source of compressed air supply. This shell 95 may be perforated in any desired 10 manner to direct currents of cool air against certain parts, particularly, however, against the soldered seam of the can body traveling above the same. No patentable novelty is claimed for this expedient other than in 15 combination with can-body advancing means of such character—as exemplified by the device herein shown and described—that the freshly soldered side seam of the advancing can body is directly exposed to air currents 20 from a contiguous source of compressed air supply.

From the foregoing description it will be seen that in the machine of my invention the free end of the horn or track 12 is at all 25 times suitably and adequately supported and yet in such manner that can bodies may be advanced along the same and discharged from the end thereof without contacting with the supporting means; that the soldering and advancing mechanisms may be instantly disconnected, at will, from the can-body-forming and other mechanisms and operated independently to clear the horn and avoid waste; that objectionable rotation of the can body advancing along the 30 horn is prevented during the soldering operation; and that I have materially simplified the combined processes of advancement, fluxing, soldering, wiping, cooling and dis- 35 charging.

Many modifications of minor details of my improved can-body side-seam soldering machine will doubtless readily suggest themselves to those skilled in the art to which 45 it appertains, and I therefore do not desire to limit my invention to the specific construction of machine herein shown and described.

I claim:

- 50 1. In a machine of the character described, the combination, with a guiding and supporting track for work which surrounds the same and means for advancing said work along said track, of a plurality of supports carried by said advancing means and traveling therewith for sustaining said track.
- 55 2. In a machine of the character described, the combination, with a guiding and supporting track for individual work units which surround the same and means for advancing said units successively along said track, of a plurality of supports carried by said advancing means and traveling therewith for sustaining said track.
- 60 3. In a machine of the character described, the combination, with a guiding and supporting track for work which surrounds the same, said track having one free end, and means for advancing said work along said track and discharging the same from the free end thereof, of a plurality of supports carried by said advancing and discharging means and traveling therewith for sustaining the free end of said track.
- 65 4. In a machine of the character described, the combination, with a guiding and supporting track for individual work units which surround the same, said track having one free end, and means for advancing said units successively along said track and discharging the same from the free end thereof, of a plurality of supports carried by said advancing and discharging means and traveling therewith for sustaining said track at points intermediate the advancing units.
- 70 5. In a machine of the character described, the combination, with a guiding and supporting track for work which surrounds the same, of an endless conveyer having means for advancing said work along said track, said conveyer also carrying means for sustaining said track.
- 75 6. In a machine of the character described, the combination, with a guiding and supporting track for individual work units which surround the same, of an endless conveyer having means for advancing said units successively along said track, said conveyer also being provided with means for sustaining said track.
- 80 7. In a machine of the character described, the combination, with a guiding and supporting track for work which surrounds the same, said track having one free end, of an endless conveyer having means for advancing said work along said track and discharging the same from the free end thereof, said conveyer also being provided with means for sustaining the free end of said track.
- 85 8. In a machine of the character described, the combination, with a guiding and supporting track for individual work units which surround the same, said track having one free end, of an endless conveyer having means for advancing said units successively along said track and discharging the same from the free end thereof, said conveyer also being provided with means for sustaining the free end of said track.
- 90 9. In a machine of the character described, the combination, with means for applying solder to the side seam of a can body in transit, said means including a track having one free end for interiorly guiding and supporting said body, and said track extending a distance beyond the soldering mechanism, and means for advancing can bodies successively along said track and through said soldering mechanism, of separate means for continuing advancement and effecting final 100
- 95 10. In a machine of the character described, the combination, with a guiding and supporting track for work which surrounds the same, said track having one free end, of an endless conveyer having means for advancing said work along said track and discharging the same from the free end thereof, said conveyer also being provided with means for sustaining the free end of said track.
- 110 11. In a machine of the character described, the combination, with a guiding and supporting track for individual work units which surround the same, said track having one free end, of an endless conveyer having means for advancing said units successively along said track and discharging the same from the free end thereof, said conveyer also being provided with means for sustaining the free end of said track.
- 115 12. In a machine of the character described, the combination, with a guiding and supporting track for individual work units which surround the same, said track having one free end, of an endless conveyer having means for advancing said units successively along said track and discharging the same from the free end thereof, said conveyer also being provided with means for sustaining the free end of said track.
- 120 13. In a machine of the character described, the combination, with means for applying solder to the side seam of a can body in transit, said means including a track having one free end for interiorly guiding and supporting said body, and said track extending a distance beyond the soldering mechanism, and means for advancing can bodies successively along said track and through said soldering mechanism, of separate means for continuing advancement and effecting final 130

discharge of said bodies, and means carried by and forming part of said last-mentioned advancing and discharging means for supporting the free end of said track.

- 5 10. In a machine of the character described, the combination, with means for applying solder to the side seam of a can body in transit, said means including a track having one free end for interiorly guiding and 10 supporting said body, and said track extending a distance beyond the soldering mechanism, and means for advancing can bodies successively along said track and through said soldering mechanism, of separate means for continuing advancement and 15 effecting final discharge of said bodies, and means carried by and forming part of said last-mentioned advancing and discharging means for supporting the free end of said track at points intermediate the advancing can bodies.

- 20 11. In a machine of the character described, the combination, with means for applying solder to the side seam of a can body in transit, said means including a track having one free end for interiorly guiding and 25 supporting said body, and said track extending a distance beyond the soldering mechanism, and means for advancing can bodies successively along said track and through said soldering mechanism, of separate means for continuing advancement and 30 effecting final discharge of said bodies, and a plurality of supports carried by said last-mentioned advancing and discharging means for supporting the free end of said track.

- 35 12. In a machine of the character described, the combination, with means for applying solder to the side seam of a can body in transit, said means including a track having one free end for interiorly guiding and 40 supporting said body, and said track extending a distance beyond the soldering mechanism, and means for advancing can bodies successively along said track and through said soldering mechanism, of separate means for continuing advancement and 45 effecting final discharge of said bodies, and a plurality of supports carried by said last-mentioned advancing and discharging means for supporting the free end of said track at points intermediate the advancing can bodies.

- 50 13. In a machine of the character described, the combination, with means for applying solder to the side seam of a can body in transit, said means including a track having one free end for interiorly guiding and 55 supporting said body, and said track extending a distance beyond the soldering mechanism, and means for advancing can bodies successively along said track and through said soldering mechanism, of an endless conveyer for continuing advancement and 60 effecting final discharge of said bodies, said 65

conveyer also being provided with means for supporting the free end of said track.

14. In a machine of the character described, the combination, with means for applying solder to the side seam of a can body in transit, said means including a track having one free end for interiorly guiding and supporting said body, and said track extending a distance beyond the soldering mechanism, and means for advancing can bodies successively along said track and through said soldering mechanism, of an endless conveyer for continuing advancement and effecting final discharge of said bodies, said conveyer also being provided with means for supporting the free end of said track at points intermediate the advancing bodies.

70 15. In a machine of the character described, the combination, with a guiding and supporting track for individual work units which surround the same, and means for advancing said units successively along said track, said means comprising an endless conveyor having spaced fingers for engaging said units, of a series of track supports carried by said conveyor each located just to the rear of one of said fingers.

75 16. In a machine of the character described, the combination, with a guiding and supporting track for individual work units which surround the same, of means for advancing said units successively along said track, said means comprising an endless conveyor having spaced fingers for engaging said units, said conveyor being also provided with a series of track-supporting rollers each located just to the rear of one of said fingers, and means for supporting said rollers throughout forward movement thereof.

80 17. In a machine of the character described, the combination, with means for applying solder to the side seam of a can body in transit, said means including a track for interiorly guiding and supporting said body extending a distance beyond the soldering mechanism and having its farther end free whereby said body may be discharged therefrom, and means for advancing can bodies in succession along said track and through said soldering mechanism, of an endless conveyor for continuing advancement and effecting final discharge of said bodies, said conveyor comprising parallel sprocket-chains, a series of equidistantly-spaced, roller-supported carriages mounted in and between said chains, and track-rails upon which the carriage-rollers run, each carriage being provided with means for engaging a can body and with means for supporting said track.

85 18. In a machine of the character described, the combination, with means for applying solder to the side seam of a can body in transit, said means including a track for interiorly guiding and supporting said body extending a distance beyond the soldering mechanism, and means for advancing can bodies successively along said track and through said soldering mechanism, of an endless conveyor for continuing advancement and effecting final discharge of said bodies, said

mechanism and having its farther end free whereby said body may be discharged therefrom, and means for advancing can bodies in succession along said track and through said soldering mechanism, of an endless conveyor for continuing advancement and effecting final discharge of said bodies, said conveyor comprising parallel sprocket-chains, a series of equidistantly-spaced carriages 10 each provided with an axle with a roller at each end thereof, and track-rails upon which said rollers run, said axles being journaled

in suitable links in said chains and each carriage being further provided with means for engaging a can body and each axle with an 15 additional roller for progressively supporting said track.

In testimony of the foregoing, I have hereunto set my hand in the presence of two witnesses.

JULIUS BRENZINGER.

Witnesses:

JAMES T. CONNOR,
L. D. JONES.
